DRAFT RIGGING

Glenn F. Couch, Rochester, N. Y., assignor to
The Symington Company, New York, N. Y., a
corporation of Maryland

Application April 19, 1932, Serial No. 606,254

10 Claims. (Cl. 213—6)

This invention relates to draft rigging and, more particularly, to a coupler and the connection thereof to a railway vehicle or locomotive pilot beam.

5 The principal object of my invention, generally considered, is the connection of a coupler with a relatively short shank to a railway vehicle in such a manner that it angles as if it were swivelled about a long radius.

10 Another object of my invention is the connection of a coupler to a locomotive pilot beam in such a manner that it may swing horizontally about a center disposed a relatively great distance rearwardly of said beam, thereby making

15 it the equivalent of a long radius coupler, and avoiding derailments, especially when the locomotive is used for pusher service.

Other objects and advantages of the invention relating to the particular arrangement and construction of the various parts will become apparent as the description proceeds.

Referring to the drawings illustrating my invention, the scope whereof is defined by the appended claims:—

20 Figure 1 is a fragmentary plan, with portions in horizontal section on the line 1—1 of Figure 2, of a coupler embodying my invention and connected to the front of a locomotive pilot beam.

Figure 2 is a transverse sectional view on the 30 line 2—2 of Figure 1, looking in the direction of the arrows.

Figure 3 is a fragmentary front elevational view of the embodiment of my invention shown in Figures 1 and 2, with portions of the mechanism 35 removed to show one of the rockers.

Figure 4 is a fragmentary sectional view on the line 4—4 of Figure 1, looking in the direction of the arrows.

Figure 5 is a view corresponding to Figure 1, but 40 showing a modification.

Figure 6 is a longitudinal sectional view on the line 6—6 of Figure 5, looking in the direction of the arrows, the coupler head and stub stem being shown in elevation.

45 Figure 7 is a side elevational view of the embodiment of my invention illustrated in Figures 5 and 6, a portion being broken away.

Figure 8 is a side elevational view of one of the rockers.

50 When utilizing a locomotive for pusher service, the pilot coupler is naturally displaced on curves a considerable extent horizontally from the center of the track, and this requires that the connected coupler on the caboose, or rear car of the train being pushed, must swing in the wrong

direction to maintain proper face contact, in some instances, swinging further than the enclosing striking casting permits, with the result that a derailment occurs. A theoretically correct solution of this problem of preventing such derailments would require that the front end of the locomotive be equipped with a coupler having a shank or adapted to swivel about a radius in the neighborhood of eight or ten feet long. The average locomotive has no spare space along its longitudinal center line for any such coupler shank. In accordance with my invention, I have devised the equivalent of a long radius coupler which can be applied to the front of the pilot beam.

Referring to the drawings in detail, like parts 15 being designated by like reference characters, and first considering the embodiment of my invention illustrated in Figures 1 to 4, inclusive, there is shown a portion of a locomotive pilot beam 1 to which is connected a base casting or bracket member 2 as by means of bolts 3 and nuts 4, said bolts 3 preferably extending through slots 5 in the base web 6 of the casting 2 to allow for vertical adjustment of said casting with respect to the beam 1.

Referring to the drawings in detail, like parts 15 being designated by like reference characters, and first considering the embodiment of my invention illustrated in Figures 1 to 4, inclusive, there is shown a portion of a locomotive pilot beam 1 to which is connected a base casting or bracket member 2 as by means of bolts 3 and nuts 4, said bolts 3 preferably extending through slots 5 in the base web 6 of the casting 2 to allow for vertical adjustment of said casting with respect to the beam 1. Inasmuch as the base web 6 of the casting 2, 25 in the present embodiment, when in the desired position, extends below the bottom of the pilot beam 1, an adapter casting 7 is desirably used to form an extension 8 to the front face of the pilot beam to receive the lower bolts 9 for securing the 30 lower portion of the base casting 2 to the pilot beam 1. Said adapter casting 7 is desirably interlocked and connected with the pilot beam 1 by having the base portion 10 fitting between the portion of the front wall 11 of the pilot beam 35 which extends below the lower web 12 thereof and a depending flange portion 13, and connected to said lower web portion 12 in any desired manner, as by means of the bolts 14 and stud 15, as shown most clearly in Figures 1 and 2. If desired, liners 40 16 may be positioned between the front face of the pilot beam 1 and adapter casting 7 and the rear face of the base casting 2.

Received in the base casting 2 is what may be termed a radial casting or radially swinging member 17. Said casting 17 is adapted to support rockers 18 in rearwardly opening pockets 19, thereby providing for radial movement, and the stub shank 20 of a pilot coupler 21 in a forwardly opening pocket 22. In the present embodiment, each 50 of the two rockers 18 has a cylindrical pivot or end portion 23 swivelled for horizontal angling in a corresponding socket 24 in the base casting 2, and flares outwardly to a toothed circumferential edge portion 25 normally engaging a correspond- 55

ing concavely curved toothed portion 26 on the radial casting 17. The toothed portion 26 on the radial casting 17 is curved to a radius about which the supported coupler is to swing.

5 In order to allow for the desired swinging of the radial casting 17, the front face 27 of the base web 6 of the casting 2 is cylindrically curved about a center corresponding with the curvature of the associated radial casting 17 and the rear face of 10 the socket portion 28 which provides the coupler stem receiving pocket 22 is correspondingly concavely curved, so that upon movement of the radial casting from side to side, there is no binding between it and the base wall 6 of the base casting 15 2, the cylindrical toothed rocking surfaces 25 of the rocker members 18 allowing the radial casting to swing about a fixed center or axis disposed rearwardly of the base casting and pilot beam a relatively great distance so as to give the supported coupler 21 the equivalent of a long shank.

In order to mount the coupler stem 20 in the radial casting 17, as well as prevent undesired withdrawal of the radial casting 17 from the base casting 2, a connecting pin or headless bolt 29 desirably extends vertically through the stem 29 and the walls of the radial casting 17, those portions of said pin 29 above and below the upper and lower webs of the radial casting 17 having mounted thereon washers or wear members 30, the sides 30 of which are desirably cylindrically curved about the center provided for the swinging of the radial casting so that the upper washer 30 is adapted to slide on the depending cylindrical flange 31 of the base casting 2 and the lower washer 30 is adapted 35 to slide on the upstanding cylindrical flange 32 of the base casting 2, thereby allowing for the radial movement of the coupler 21 on draft, it being understood that the rockers 18 allow for such radial movement on buff. Of course, it will be 40 understood that the rear or bearing surfaces on the flanges 31 and 32 are curved about a center or axis corresponding with the center or axis of the curved and toothed front wall or web 26 of the radial casting 17.

45 To provide for insertion and removal of the pin 29, the upper web 33 of the base casting 2 is shown apertured, as indicated at 34, said aperture being normally closed by a cap 35 held in place by a retainer or cotter 36. In the preferred embodiment 50 illustrated, the washers 30 are comparatively loose on the pin 29, so that they may be inserted before the assembly of the radial casting 17 with the base casting 2 and the pin 29 simply dropped to position after assembly of the other parts. In 55 order to allow for convenient removal of the pin 29, a relatively small hole 37 is provided in the lower web portion 38 so that when the cap 35 is removed, the pin may be pushed out of the aperture 34 by a bar inserted in the hole 37. In order to allow for the convenient taking up of wear 60 between the pin 29 and shank 20 of the coupler 21, the apertured portion of said shank desirably has a bushing 39 applied thereto. The lower web 38 of the base casting is desirably extended, as indicated at 40, to underlie the head of the coupler 21 and prevent drooping.

70 Referring now to the embodiment of my invention illustrated in Figures 5 to 8, inclusive, a construction is there disclosed which corresponds substantially with that of Figures 1 to 4, inclusive, except that the pin 29^a connecting the coupler stem 20^a with the radial casting 17^a has bushings 39^a and rollers 30^a on the ends thereof, instead of washers as in the preceding embodiment. This 75 allows for rolling action on the vertical flanges

31^a and 32^a of the base casting 2^a, instead of sliding action as in the preceding embodiment. A further difference resides in the fact that drooping of the coupler 21^a is prevented by extension of the lower portion of the radial casting 17^a to engage the base casting extension 40^a, rather than having said extension directly engage the coupler head. 5

In the present embodiment, the rockers 18^a are shown each provided with a single tooth 25^a, instead of three teeth as in the preceding embodiment, each tooth fitting in a corresponding aperture in the circumferential front web 26^a of the radial casting 17^a, said apertures being framed by outstanding beading 41 in order to protect the 10 teeth 25^a which, as will be understood, are relatively long in order to provide the desired guiding action for the full swivelling movement of the coupler. The opening to the coupler stem pocket 22^a is likewise desirably framed by beading 42 of 15 radial dimension corresponding with the beading 41. As in the preceding embodiment, the base casting 2^a may be connected to an associated pilot beam (not shown) with the aid of an adapter casting (not shown), if desirable or necessary. 20 In the present embodiment, the aperture 34^a allowing for insertion and removal of the pivot pin 29^a is disposed off-center, so that the pin will normally be retained in position by the top web 33^a of the base casting 2^a without the necessity of 25 a retaining cap. Except as specifically described and illustrated, the embodiment of Figures 5 to 8, inclusive, may correspond with the first described embodiment.

30 From the foregoing disclosure, taken in connection with the accompanying drawings, it will be seen that I have provided for the mounting of a locomotive coupler in such a manner that it may move horizontally in service as if it were pivoted about a center disposed a relatively great 35 distance rearwardly of the pilot beam without weakening the beam or interfering with the normal front end structure of the locomotive by the provision of an unusually long shank on the 40 coupler. 45

Although preferred embodiments of my invention have been disclosed, it will be understood that modifications may be made within the spirit and scope of the appended claims.

50 I claim:—

1. In a device of the character indicated, in combination with a base member adapted to be rigidly secured to a locomotive, a radially swinging member supported by and movable with respect to said base member, said swinging member having a forwardly opening pocket receiving a coupler stem, and a pin connecting said stem to said swinging member, said pin extending above and below said swinging member to overlap portions of the base member and retain the 60 parts in assembled relation. 55

2. In a device of the character indicated, in combination with a locomotive pilot beam with normally horizontal and vertical web portions, said vertical web portion being continued below 65 the lower face of the horizontal web portion, a base casting with a web secured to the front face of said vertical web portion and extending below the lower edge thereof, an adapter casting with a portion engaging said lower face behind said 70 extension, connected to the horizontal web of said beam and provided with a web extending from behind said extension and below said beam in line with the front face of said vertical web portion, means connecting the lower portion of 75

said base casting web to said adapter casting, a radially swinging member mounted in said base casting, and a coupler connected to said swinging member.

5. 3. In a device of the character described, in combination with a pilot beam, means providing a forwardly opening recess at the front thereof, means providing inwardly extending shoulders partly closing said recess, a casting having a 10 rounded end portion extending into the recess, means for pivotally uniting said casting to said beam, rocker members seated in said recess and adapted to engage the casting, said rocker members and said pivotal means serving respectively 15 to take the force of buffing and draft imparted to said casting, a coupler with a stem extending into said casting between said rockers, and means securing said stem in place.

4. In a device of the character indicated, the 20 combination with a casting adapted to be rigidly secured to a railway vehicle and provided with a pocket, of a member received in said pocket, means connecting said member and casting for the transmission of draft forces, while allowing 25 radial swinging of the former with respect to said casting about an axis lying outside of said member, rocker means in said pocket and interposed between said casting and said swinging member so as to allow for said swinging and 30 serve to transmit buffing forces from said member to said casting, and a coupler carried by said swinging member.

5. In a device of the character indicated, in combination with a base casting adapted to be 35 rigidly secured to a railway vehicle and provided with a forwardly opening pocket, of a radial casting received in said pocket, means adapting said radial casting to swing with respect to said base casting about an axis disposed to the rear of said 40 radial casting and serving to transmit draft forces therebetween, rocker means in said pocket, pivoted with respect to said base casting, and interposed between it and said radial casting so 45 as to transmit buffing forces therebetween, and a coupler with a stem received in a forwardly opening pocket in said radial casting.

6. In a device of the character indicated, the 50 combination with a casting adapted to be rigidly secured to a railway vehicle, of a radially swinging member supported by and movable with respect to said casting, a coupler carried by said swinging member, draft force transmitting means connecting said coupler, swinging member and casting, and a plurality of rockers interposed between said casting and said swinging member, each of said rockers having end portions swiveled 55 in sockets in said casting and circumferential

portions adapted to roll on portions of said swinging member.

7. In a device of the character indicated, the combination with a base casting adapted to be rigidly secured to a locomotive, of a radial casting supported by and movable with respect to 5 said base casting and provided with concavely curved surfaces facing the latter, a coupler carried by said radial casting, and rocker means interposed between said base casting and radial 10 casting, said rocker means having end portions movable with respect to said base casting and circumferential portions normally rolling on the curved surfaces and having toothed engagement with said radial casting. 15

8. In a device of the character indicated, in combination with a bracket member adapted to be rigidly secured to a railway vehicle, a radially swinging member supported by and movable with respect to said bracket member, said swinging 20 member having a concave surface curved to correspond with the desired radius of swinging, rocker means disposed between said bracket member and radially swinging member, engaging said concave surface, and serving to allow 25 for swinging and transmit buffing forces therebetween, and a coupler carried by said swinging member.

9. In a device of the character indicated, in combination with a base member adapted to be 30 rigidly secured to a railway vehicle and having a forwardly opening pocket, a radially swinging member supported in said pocket and movable with respect to said base member, said swinging member having a surface concavely curved to 35 correspond with the desired radius of swinging, rockers movably engaging said base member and with convex surfaces engaging said concavely curved surface on the swinging member to allow for swinging and transmit buffing forces therebe- 40 tween, and a coupler carried by said swinging member.

10. In a device of the character indicated, in combination with a base member adapted to be rigidly secured to a railway vehicle and having 45 a forwardly opening pocket, a radially swinging member received in said pocket and movably supported by said base member, said swinging member having a rearwardly facing concave surface, rockers disposed in said pocket between said base 50 member and the concave surface of said swinging member to transmit buffing forces and reduce friction during relative movement, said swinging member having a forwardly opening pocketed portion disposed between said rockers, and a cou- 55 pler with a shank extending into said pocketed portion and connected to said swinging member.

GLENN F. COUCH.
